Inventor:

Alexander Archangelsky
Rudolf Grunberg Jr.

UNITED STATES PATENT OFFICE

ALEXANDER ARCHANGELSKY AND RUDOLF GOLDBERG, OF BERLIN, GERMANY

TELEPHONE ARRANGEMENT

Application filed June 4, 1928, Serial No. 282,806, and in Germany January 12, 1926.

In telephones it is known to have a combined microtelephone and a separate casing containing the accessories, an electric cable connecting both said parts. It is further known to suspend such microtelephones on an electric or other cable, which for this purpose is guided by an overhead roller.

The invention consists therein that a microtelephone is suspended on a cable influenced by a counterweight in such manner as to give the microtelephone automatically an upward tension, and the microtelephone is provided with a device adapted to be fastened below the chin or on the clothes of the user so as to be automatically held in the use position on the head. In this way the user has both hands free during telephoning and is able to make notices and do other work.

Further details of the invention will appear below.

In the drawing the invention is illustrated in several embodiments in simplified manner.

Fig. 1 shows an arrangement with a table casing,

Fig. 2 shows an arrangement with a wall casing;

Fig. 3 shows an arrangement with a modified suspension,

Fig. 4 shows in an enlarged perspective view a microtelephone with chin bow.

According to Fig. 1 a casing 1 of a table telephone is mounted by side near a wall on a bracket. A switch rod 2 is held down by two screw springs 3, fastened to the bracket, onto the telephone fork 1' provided for receiving the microtelephone. The telephone cable 4, coming from the casing 1, is fastened to said switch rod 2 and guided over overhead rollers 5, 6 to the microtelephone consisting of a telephone 7, a handle 8 and a microphone 9. The springs 3 are as strong as to overcome the weight of said microtelephone 7-9, so that they endure a resting position in which the telephone fork 1' is pressed down and the speaking current is interrupted in usual way. For allowing the microtelephone to be drawn farther away than allowed by the springs 3, a rolling weight 10 is applied to the cable 4 so as to

produce in the latter a yielding loop. As for raising the weight 10 the tension in the cable may be augmented by pulling down the microtelephone, this augmented tension overcomes the springs 3 and causes the fork 1' to raise and the speaking circuit to be closed.

According to Fig. 2 in a device corresponding to that shown in Fig. 1 and designed by the same reference numerals, instead of a table telephone a special switch 11 is connected to the cable 4 for effecting the closing and interrupting of the calling and speaking circuits in the same way as the telephone fork 1' (Fig. 1) or a telephone hook. This switch casing 11 allows a table telephone or wall telephone to be connected to it without necessitating any alterations on the telephone casing.

According to Fig. 3 in a similar arrangement near the first roller 5 an additional roller 12 is applied to the cable 4, so that from the rolling weight 10 both cable parts run straight upward, and the rolling weight 10 is positioned straight over the telephone fork 1', so as to rest on the latter and press it down as long as no pull is exerted on the microtelephone 7-9. Hereby no springs are needed, and the cable 4 has an essentially equal tension in all positions, which for the use is a special advantage. The operation corresponds to that of the first embodiments.

According to Fig. 4 for all embodiments the microtelephone 7-9 is provided with a wire bow 13 adapted to be put under the chin of the user and having a part 13' fitting round the user's throat in such manner, that under the upward pull of the cable 4 the microphone 9 is held near to the mouth and the telephone 7 against the ear of the user.

A push button 14 is provided on the handle 8 of the microtelephone for short circuiting the microphone or interrupting the speaking current or the like purposes. A line selector 5 in the form of a sledge or rolling band is inserted for the case, that line selection shall be provided and the selector shall not remain in the usual table or wall casing. The cable 4 contains the several conductors needed for such purposes.

We claim:

1. A telephone arrangement comprising in combination a microtelephone, a cable connected to said microtelephone, means for guiding said cable upward, means for exerting an upward tension in said cable overcoming the weight of said microtelephone, and means on said microtelephone adapted to be fixed on the user for holding it on the head of the user against said tension.
- 10 2. A telephone arrangement comprising in combination a microtelephone, a cable connected to said microtelephone, means for guiding said cable upward, means for exerting an upward tension in said cable overcoming the weight of said microtelephone, and a bow on said microtelephone, fitting to the lower side of the chin of a user.
- 15 3. A telephone arrangement comprising in combination a microtelephone, a cable connected to said microtelephone, means for guiding said cable upward, means for exerting an upward tension in said cable overcoming the weight of said microtelephone, a bow on said microtelephone, fitting to the lower side of the chin of a user, and a part on said bow, fitting round the throat of a user.
- 20 4. A telephone arrangement comprising in combination a microtelephone, a cable connected to said microtelephone, means for guiding said cable upward, means for exerting an upward tension in said cable overcoming the weight of said microtelephone, means on said microtelephone adapted to be fixed on the user, for holding it on the head of the user against said tension, and a switch operatively connected to said cable so as to close the speaking circuit at a pull exerted on the cable and interrupt said circuit at relieving said pull.
